PLAQUE

Daniel J. Hennessy, New York, N. Y.

Application September 26, 1951, Serial No. 16,749

Term of patent 14 years

(Cl. D29—23)

To all whom it may concern:

Be it known that I, Daniel J. Hennessy, a citizen of the United States, residing in the city, county, and State of New York, have invented a new, original, and ornamental Design for a Plaque, of which the following is a specification, reference being had to the accompanying drawings, forming a part thereof, in which

Fig. 1 is a front elevational view of a plaque, showing my new design.

Fig. 2 is a top plan view thereof.

The essential features of my design reside in the portions shown in full lines.

I claim:

The ornamental design for a plaque, substantially as shown and described.

DANIEL J. HENNESSY.
